UNITED STATES PATENT OFFICE.

GEORGE B. THOMAS, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

ELECTRIC SWITCH.

1,272,147.

Specification of Letters Patent.

Patented July 9, 1918.

Application filed February 16, 1916. Serial No. 78,679.

To all whom it may concern:

Be it known that I, GEORGE B. THOMAS, a citizen of the United States of America, and residing at Bridgeport, in the county of 5 Fairfield and State of Connecticut, have invented a certain new and Improved Electric Switch, of which the following is a specification.

My invention relates to electric switches 10 and particularly to an electric switch adapted to be mounted directly upon the bus bars of a panel board, the object of my invention being to provide a switch of economical and appropriate construction for this purpose.

15 In the accompanying drawings,

Figure 1 is a perspective of panel board bus bars and associated therewith a switch embodying my invention;

Fig. 2 is a vertical section through the 20 same on the line 2—2, Fig. 1;

Fig. 3 is a vertical section at right angles to Fig. 2;

Fig. 4 is a horizontal section on the line 4—4, Fig. 2; and

25 Fig. 5 is a perspective of a detail.

With the increasing use of panel boards in 30 residences of the larger sort and in office buildings there has arisen a demand for a snap switch mechanism of relatively low 35 capacity for controlling the branch circuits led from the panel board. The object of my invention is to adapt a standard switch mechanism construction to such use and provide a suitable housing to inclose and insulate the switch mechanism.

The switch mechanism proper, illustrated 40 in the accompanying drawing, is of common construction and of the general type illustrated in my Patent 1,046,899 in which the operating mechanism 10, switch blades 11, and switch terminals 12 are mounted upon a suitable insulating base 13 which is adapted 45 to be inserted in a cup-like receptacle having combined wire terminals and straps 50 adapted to coöperate with the switch terminals 12 when the switch body 13 is inserted in the cup-shaped receptacle. Inasmuch as the bus bars take the place of the wires on the panel board as the conductors, it is obviously impossible to use a receptacle 55 such as that denominated A in the patent above referred to. The current is led from the bus bars to the switch terminals accord-

ing to the present invention by means of standards 14 secured by screws 15 to the 55 several terminals on the one hand, and provided with offset bases 14* which are secured by screws 16 to the several bus bars 17. In this way the switch mechanism is not only mechanically supported upon the panel 60 board but its switch terminals are electrically connected to the appropriate bars.

Inasmuch as a suitable housing must be provided to inclose the switch against accidental contact as well as against dirt and 65 moisture, I provide a cover 18 of insulating material in the form of an inverted cup through holes 19 in the base of which pass the push buttons 20 for operating the switch 70 mechanism. The sides of the cover completely inclose the switch mechanism and contacts and is notched away at the four corners at 21 to permit the entry of the bus bars into the closed switch chamber formed by 75 the cover. Set into the upper face of the insulating base 13 is a strap 22 the tapped holes 23 in which receive the securing screws 24 by which the switch frame 25 is mounted thereon. At the opposite ends of the strap 80 is a second pair of tapped holes 26 which receive the screws 27 passing through countersunk holes in the cover and securing the latter to the strap and thus to the switch mechanism which is firmly held by the four screws 16 upon the panel board.

85 The present construction affords an efficient switch mechanism of standard construction and readily adapted from the ordinary flush switch type to the panel board type disclosed by the use of the standards 90 14 secured to the terminal straps 12. Various modifications and adaptations of my invention will readily occur to those skilled in the art without departing from what I 95 claim as my invention.

I claim as my invention:—

1. A panel board switch comprising a “removable-mechanism” flush switch insulating base with the usual switch mechanism and combined switch terminals and brush contacts mounted thereon, in combination with independent standards secured to the brush portions of said contacts, means for securing said standards directly to the bus bars of a panel board to electrically connect 105 the latter to said switch terminals, an insu-

lating hood inclosing said base and electrical connections and switch-operating means projecting through said hood.

2. A panel board switch comprising a "re-
5 movable-mechanism" flush switch insulating base with the usual switch mechanism and combined switch terminals and brush contacts mounted thereon, in combination with independent standards secured to the
10 brush portions of said contacts, screw means for detachably securing said standards directly to the bus bars of a panel board to

electrically connect the latter to said switch terminals, an insulating hood inclosing said base and electrical connections and switch-
operating means projecting through said hood.

In testimony whereof I have signed my name to this specification, in the presence of two subscribing witnesses.

GEORGE B. THOMAS.
